UNITED STATES PATENT OFFICE.

ADAM A. SERVA, OF CANTON, OHIO, ASSIGNOR TO THE UNITED ELECTRIC COMPANY, OF CANTON, OHIO, A CORPORATION OF OHIO.

ROTARY DRIVE FOR VACUUM CLEANERS.

Original application filed September 23, 1922. Serial No. 590,113. Divided and this application filed November 3, 1923. Serial No. 672,626.

This invention relates to rotary brushes for use upon vacuum cleaners or similar devices and the objects of the improvement are to provide a simple and efficient means for rotatably mounting the brush in the casing of the cleaner and providing for rotating the brush from a traction wheel of the cleaner.

The above and other objects may be attained by constructing the device as illustrated in the accompanying drawing, in which—

Figure 1 is a bottom plan view of the nozzle and brush of a vacuum cleaner, parts being shown in section; and

Fig. 2, an enlarged sectional view of the bearing and driving means to which the invention pertains.

Similar numerals refer to similar parts throughout the drawing.

For the purpose of illustrating the application of the improvement to a vacuum cleaner, a portion of a vacuum cleaner of any usual type is illustrated and includes the nozzle 1 connected in usual manner to a suction chamber and arranged to be supported upon the floor by the wheels 2.

The rotary brush 3 is of usual construction and is mounted for rotation within the nozzle 1, one end of the brush shaft which is preferably hollow, being inserted over the sprung pressed plunger 4 in the adjacent end of the nozzle, providing a journal bearing for this end of the brush, the other end of the brush shaft having a transverse pin 5 which engages the transverse slot 6 in the pulley shaft 7, the pulley 8 being fixed or formed integral upon said shaft and con-

nected as by the belt 9 with the adjacent traction wheel 2 which is grooved as at 10 to receive the belt.

A brass brushing 11 is mounted in the inner wall 12 of the nozzle and forms one bearing for the pulley shaft 7, a screw cap 13 being inserted into the outer wall 14 of the casing and provided with a brass bushing 15 which serves as the outer bearing for the shaft.

With this construction of driving mechanism for the brush, it is possible to form the pulley of relatively small diameter to cooperate with the grooved traction wheel, in order to rotate the brush at a substantially high speed.

By forming the pulley shaft as above described, the same may be quickly and easily disconnected from the brush, in order to allow the brush to be removed for cleaning, and the shaft may be easily and readily replaced in the cleaner and connected to the brush.

This application is a division of my co-pending application Serial No. 590,113 filed September 23, 1922.

I claim:—

In a vacuum cleaner, the combination of an inlet nozzle, a bearing in one end thereof, a traction wheel at said end, a casing therefor, a screw cap in the outer wall of said casing having a bearing therein in alignment with the first bearing, a short shaft journaled in said bearings and having a pulley geared to said traction wheel and a brush detachably connected to said shaft.
